UNITED STATES PATENT OFFICE.

OTTO GRÜNEWALD, JR., OF NEW YORK, N. Y., AND GEORGE BASIL HOOPER,
OF NEWARK, NEW JERSEY, ASSIGNORS TO THE J. L. MOTT IRON WORKS,
OF NEW YORK, N. Y.

DESIGN FOR A DRINKING-FOUNTAIN BASE.

SPECIFICATION forming part of Design No. 34,588, dated May 28, 1901.

Application filed April 26, 1901. Serial No. 57,631. Term of patent 14 years.

To all whom it may concern:

Be it known that we, OTTO GRÜNEWALD, Jr., residing in the borough of Bronx, city and State of New York, and GEORGE BASIL HOOPER, residing at Newark, in the county of Essex and State of New Jersey, citizens of the United States, have invented and produced a new and original Design for a Drinking-Fountain Base, of which the following is a specification, reference being had to the accompanying drawings, forming part thereof, and in which—

Figure 1 is an elevation representing the obverse side of the fountain. Fig. 2 is an elevation representing the reverse side of the fountain, and Fig. 3 is a side elevation of the same.

As shown in the drawings, the leading or material features of our design consist of the rectangular base, the ornamental shape of the bowls, the molded cornice above the bowls, the dolphin, shell and scroll ornaments above the cornice on the obverse and reverse sides, the turned bar ornaments above the cornice on the sides and the corner leaflet and scroll ornaments of the upper part of the fountain.

Extending around and above the base 1 is the leaf-and-dart ornamentation 2, and above which latter is the molded portion 3. On the respective sides are the plain surfaces 4, the recessed surfaces 5, and the plain panels 6 in the sides and longitudinally-disposed panel 7 on the obverse side. Above the plain surfaces 4 is an ornamental girdle 8.

On each side of the base, above the girdle 8, is a flat portion 9, having oblong vertically-arranged recesses with rounded ends disposed in groups and intermediate rosettes. Above the flat portion 9 is a molded cornice comprising the flat surface 10 and flat edge 11 and intermediate egg-and-dart ornament 12, above which the inclined top surrounds the fountain.

On the respective sides are the flat faces 13, having on the obverse of the fountain the dolphin ornament 14 and the scroll ornaments 15, disposed upon either side in opposite directions, and on the reverse side the shell or-

nament 16 and the scroll ornaments 15. On the side faces 13 are the horizontally-disposed turned bar ornaments 17.

The upper part of the fountain comprises the leaf-and-dart molding 18, the leaf-and-scroll-ornamented corners 19, receding upwardly, the concave faces 20, in which are the panels 21, having the floral leaflet ornament 22 in the panel of the reverse side and the leaflet ornaments in the two side panels, the twisted tail of the dolphin occupying the panel 21 in the obverse side. The cornice at the top of the fountain comprises the egg-dart and inclined moldings 23 24. The flat edge 25 and the flat beveled receding top 26 surmount the fountain.

On the front or obverse side of the fountain is the bowl 27, whose rim, extending out from the base, corresponds with and is in the same horizontal line with the ornamental girdle 8, and below which are the bands 28 and the tapering convex radial ribbed surface 29, which terminate in a corbel ornament 30 against the recessed face 5 above the panel 7. At either side of the bowl 27 and vertically disposed are the ornamental leaflet and scroll brackets 31. On the opposite side of the fountain and extending from the recessed face is the large bowl 32, having the molded rim 33, semicircular recess 34, and tapering convex radial ribs 35, and smaller intermediate ribs, all converging on the under surface at a knob 36. Projecting from the sides of the base are the smaller bowls 37, the under convex surfaces of both of which have radial tapering recesses.

Having now described our invention, what we claim as new, and desire to secure by Letters Patent, is—

The design for a drinking-fountain base substantially as herein shown and described.

Signed by us this 23d day of April, 1901. 90

OTTO GRÜNEWALD, JR.
GEORGE BASIL HOOPER.
